UNITED STATES PATENT OFFICE.

WILLIAM W. SHIRLEY, OF BUFFALO, NEW YORK.

FAN ATTACHMENT FOR ROCKING-CHAIRS.

1,110,652.

Specification of Letters Patent. Patented Sept. 15, 1914.

Application filed November 10, 1913. Serial No. 800,020.

To all whom it may concern:

Be it known that I, WILLIAM W. SHIRLEY, a citizen of the United States, residing at Buffalo, in the county of Erie and State of New York, have invented new and useful Improvements in Fan Attachments for Rocking-Chairs, of which the following is a specification.

This invention relates to fan attachments for rocking chairs and cradles in which the fan is automatically vibrated by the rocking motion of the chair or cradle.

The object of my invention is the production of a neat and simple attachment of this character which can be manufactured at small cost and which is not liable to get out of order.

In the accompanying drawings: Figure 1 is a side elevation of a rocking chair equipped with the improved attachment. Fig. 2 is a rear elevation of the lower portion of the chair and the mechanism attached thereto. Fig. 3 is a perspective view of the weighted lever and adjacent parts. Fig. 4 is a top plan view of the upper portion of the attachment. Fig. 5 is a horizontal section on line 5—5, Fig. 1, showing the upper fastening means of the device.

Similar characters of reference indicate corresponding parts throughout the several views.

1 indicates a substantially upright rock shaft preferably arranged centrally at the back of the chair and extending above and below the back. This shaft is journaled near its lower end in a bracket 2 rigidly secured preferably to the underside of the chair-seat and near its upper end in a tube or bearing 3 arranged in a bracket or collar 4 carried by the chair-back. The bracket 4 shown in the drawings has a plate 5 shaped to conform to the curved upper cross-bar 5¹ of the chair-back and detachably secured thereto by suitable clamps 6. The tube 3 is preferably movably clamped in the collar 4 which latter has a thumb or set screw 7 for this purpose.

At its lower end the shaft 1 carries a rock arm 8 connected by a link 9 with a weighted lever 10 preferably arranged underneath the chair-seat and mounted on a transverse pin 11 carried by the front end of the bracket 2. In the construction shown, the front end of this link is connected with the upper arm of

the weighted lever by a universal joint consisting of a transverse pin 12 capable of oscillating in an opening in said lever and having a vertical opening through which the angular or downwardly-bent front end of the link passes, as best shown in Fig. 3. 55 The lever 10 carries a comparatively heavy weight 13 which may be adjustably attached thereto by bolts 14 passing through one or more sets of a vertical row of registering holes formed in said lever and the shank 15 60 of the weight.

To the projecting upper end of the rock shaft 1 is secured a gear wheel or segment 16 by a set screw 22 or other fastening. This segment meshes with a pinion 17 secured to 70 a substantially horizontal rock shaft 18 arranged on the front side of the shaft 1 and overhanging the chair seat. This pinion-shaft is supported in a frame 19 secured to the upper end of the bearing tube 3 by a set 75 screw 20, or other suitable means. The shaft 18 carries at its front end a suitable fan 21 preferably arranged in a pendant position over the user's head.

In rocking the chair, the weight 13 tends 80 to hold the lever 10 in a substantially vertical position, and this lever in turn holds the link 9 against longitudinal movement. The upright rock shaft 1 moves back and forth with the chair-back and seat and the 85 rock-arm 8 tends to follow these movements of said shaft, but as the link 9 is practically held stationary, said rock arm 8 is swung forward on the rearward stroke of the chair and swung backward on the forward stroke 90 of the chair, thereby rocking the shaft 1 which in turn actuates the shaft 18 and the fan 21 attached thereto.

As the weighted lever is located underneath the chair seat, it is out of the way and does not render the chair unsightly. None of the parts of the attachment are mounted on the arm rests of the chair and the device therefore in no way interferes with the comfort or convenience of the occupant of the 100 chair.

Should it be desired to move the fan out of the way, this can be easily done by loosening the set screw 7 and reversing or swinging the frame 19 and the fan shaft, together 105 with the tube or bearing 3, around to the rear side of the chair-back.

The attachment can be readily applied to

the seat and the back of any ordinary rocking chair, as shown, or to the bottom and the side of a cradle.

I claim as my invention:

- 5 In an automatic fan attachment for rocking chairs, the combination of a bracket adapted to be secured beneath the chair-seat, a weighted lever pivoted to said bracket, a substantially upright rock shaft
10 supported on the back of the chair and provided with a rock arm, a connection extending from said rock arm to said weighted

lever, a gear segment secured to the upper portion of said rock shaft, and a substantially horizontal fan-shaft extending forwardly from the upper portion of said upright shaft, the fan-shaft having a pinion which engages said segment. 15

Witness my hand this seventh day of November, 1913.

WILLIAM W. SHIRLEY.
